UNITED STATES PATENT OFFICE.

ROBERT A. RUSSELL, OF NEW YORK, N. Y., ASSIGNOR, BY DIRECT AND MESNE ASSIGNMENTS, OF ONE-THIRD TO PARAGON METAL CAP COMPANY, INC., OF BROOKLYN, NEW YORK, A CORPORATION OF NEW YORK, ONE-THIRD TO MARTIN KING, OF NEW YORK, N. Y., AND ONE-THIRD TO LESLIE R. N. CARVALHO, OF BROOKLYN, NEW YORK.

CAP FOR BOTTLES OR JARS.

1,327,967.

Specification of Letters Patent.

Patented Jan. 13, 1920.

Application filed April 2, 1915. Serial No. 18,706.

To all whom it may concern:

Be it known that I, ROBERT A. RUSSELL, residing at New York, in the county of New York and State of New York, have invented certain new and useful Improvements in Caps for Bottles or Jars, of which the following is a specification.

The invention relates to new and useful improvements in caps for bottles or jars and more particularly to caps made from sheet metal by cutting and bending in contradistinction to being drawn.

The purpose of the invention is to provide a metal cap which may be made from sheet metal which has been lacquered prior to the forming of the cap and to produce a cap wherein the exposed surfaces in the finished cap are entirely covered by the lacquer.

20 In the drawings, which show by way of illustration one embodiment of the invention, Figure 1 shows a sheet metal blank bent to form the cylindrical body portion of the cap;

25 Fig. 2 is a top plan view of the same;

Fig. 3 is a longitudinal sectional view, showing the top inserted in the cylindrical body portion and prior to the bending of the body portion and top to join the same;

30 Fig. 4 is a longitudinal sectional view through the finished cap;

Fig. 5 is a side view of the same;

Fig. 6 is a top plan view;

35 Fig. 7 is a detail in section showing a modified form of cap; and

Fig. 8 is a view of the blank employed illustrating the manner of cutting out the parts entering into the formation of the cap shown in the other figures.

40 The invention consists generally in a sheet metal cap which is made from sheet metal having its surfaces coated with lacquer prior to the formation of the cap and wherein the cap is formed by cutting and bending the metal in contradistinction to drawing the metal. The body portion of the cap is cut from the sheet metal and formed into a cylinder and its edges are united in such a manner as to conceal and 45 cover the raw edges of the metal formed in the cutting of the blank. The top of the

cap is also cut from the lacquered sheet and is attached to the cylindrical body portion in such a manner that the raw edges of the metal formed in the cutting of the top 55 and the raw edges of the material at the upper edge of the cylindrical body portion are both concealed or covered. The lower edge of the cylindrical body portion may also be formed so as to cover the raw edges 60 of the material so that in the finished cap all the exposed surfaces of the cap will be lacquered.

Referring more in detail to the drawing, my improved cap consists of a body portion 65 1 and a top 2. This body portion 1 is formed by cutting a blank from a sheet of metal after the same is coated with lacquer as above noted. The blank is then rolled into cylindrical form and the meeting edges 70 joined by interlocking the edges, as clearly shown in Fig. 2, so that the edge 3 entirely covers and conceals the raw edge 4, while the folded edge 5 entirely covers and conceals the raw edge 6. It will be understood 75 that by the raw edge of the metal, I have reference to the exposed steel formed in the cutting of the coated sheet of steel. These raw edges if exposed will rust and corrode, but by the above construction of seam, 80 I am able to entirely cover and conceal these raw edges of the metal.

The side seam 7 of the cylindrical body portion 1 terminates short of the top, as clearly shown in Fig. 1. The top for the 85 body portion is also cut from a sheet of metal coated with lacquer, and said sheet may also be ornamented in any desired way, as illustrated for example in Fig. 6. It will be understood that the sheet after being coated 90 is ornamented, and then the disks to form the tops are cut, so that the ornamentation is properly centered in each disk. The disk forming the top 2 is bent so that the edges are turned upwardly as at 8, (see 95 Fig. 3). This top is then inserted in the cylindrical body portion 1 of the cap, and is crowded into the same a sufficient distance so the edge 9 of the body portion extends above the extreme upper edge 10 of 100 the top 2. The upper edge of the body portion 9 is then bent by means of a die or

- otherwise, about the edge 8 of the top. At the same time that this die is operating to fold or bend the upper edge of the body portion over the upwardly extending edge of the top, the center part of the top is crowned upwardly, as at 11, so as to bring the upper outer face of the top substantially into the plane of the extreme upper edges of the seam joining the top to the body of the cap. This crowning of the top brings the ornamented surface thereof flush with the top of the cap, and it also bends the metal so as to further conceal and cover the raw edge of the metal at the upper edge of the body of the cap.

Referring to Fig. 4, it will be noted that the edge 8 is folded within the bent over part of the upper edge of the body of the cap, while the edge 9 of the body of the cap is folded in between the edge 8 and the upwardly crowned part of the top, so that both of these raw edges, as above noted, are entirely covered and concealed. The cap may be then formed with a screw thread 12, by which it is attached to a suitable screw thread at the mouth of the bottle or jar in the usual manner. It may also be formed with vertical ribs, as at 13, which assist in turning the cap to screw the same on or off from the bottle or jar. These vertical ribs and the screw threads of the cap, are of the usual construction, and have no part in my present invention.

From the above construction, it will be apparent that I have provided a metal cap wherein the entire cap is made by cutting and bending the metal and the top is joined firmly to the body portion of the cap by a seam wherein the raw edges of the material are entirely concealed and covered.

In Fig. 7 of the drawings I have shown a slightly modified form of the invention, as the cap, as shown in this figure, has the lower edge thereof rolled or folded, as at 14, so as to prevent forming a sharp edge of metal at the lower edge of the cap, and, furthermore, to substantially conceal and cover the exposed or raw edge of metal formed in the cutting of the blank for the body portion of the cap.

From the above construction it will be apparent that in Fig. 7 I have shown a construction of cap wherein all the raw edges of metal formed in cutting the metal from the sheet are substantially covered and concealed.

It will be clearly apparent from the disclosure in Fig. 8 of the drawings how the edges of the parts 1 and 2 happened not to be coated with lacquer or the like. Even though the sheet of material H is coated upon one or both of its surfaces yet when the parts 1 and 2 are stamped out therefrom, as indicated, the edges of said parts where they are cut from the sheet will have

no lacquer or other coating upon them and would soon rust and destroy the appearance and efficiency of a cap of the class herein described, unless efficiently concealed and protected.

70

While I have described my invention as particularly adapted for forming a bottle cap from lacquered sheet metal, it is to be understood that the metal may be coated with other substances than lacquer and if 75 metal is used it must be of a character to provide a non-corroding surface.

It is obvious that minor changes in the details of construction may be made without departing from the spirit of the invention as set forth in the appended claims.

Having thus described my invention what I claim as new and desire to secure by Letters Patent is:

1. A lacquered sheet metal cap for bottles or jars comprising a body portion cut from sheet metal lacquered on both surfaces thereof throughout, said body portion being bent into cylindrical form and having the meeting edges thereof joined by an interfolded seam which conceals and covers the exposed raw edges of the metal formed in cutting the body portion, and a top for closing the end of said body portion, said top being cut from a sheet of metal lacquered on both sides thereof throughout, said top being joined to the body portion by an interfolded seam which conceals and covers the exposed raw upper edge of the metal of the body portion and the exposed raw edge of 100 the metal of the top formed in cutting the top.

90

2. A lacquered sheet metal cap for bottles or jars comprising a body portion cut from sheet metal lacquered on both surfaces 105 thereof throughout, said body portion being bent into cylindrical form and having the meeting edges thereof joined by an interfolded seam which conceals and covers the exposed raw edges of the metal formed 110 in cutting the body portion, and a top for closing the end of said body portion, said top being cut from a sheet of metal lacquered on both sides thereof throughout, said top being joined to the body portion by an interfolded seam which conceals and covers the exposed raw upper edge of the metal of the body portion and the exposed raw edge of 115 the metal of the top formed in cutting the top, said top being bent so as to be substantially flush with the extreme upper part of the seam joining the top to the body portion, the lower edge of said body portion being bent upwardly to conceal the raw edge of the metal at the bottom of the body portion and to stiffen the body of the cap, said body portion having a screw-thread formed therein.

110

3. A sheet metal cap for bottles comprising a body portion cut from sheet metal 120

125

130

coated on both surfaces thereof throughout, said body portion being bent into cylindrical form and having the meeting edges thereof joined by an interfolded seam which 5 conceals and covers the exposed raw edges of the metal formed in cutting the body portion, and a top for closing the end of said body portion, said top being cut from a sheet of metal coated on both sides thereof 10 of throughout, said top being joined to the body portion by an interfolded seam which conceals and covers the exposed raw upper edge of the metal of the body portion and the exposed raw edge of the metal of the top formed in cutting the top, the lower 15 edge of said body portion being bent upwardly to conceal the raw edge of the metal at the bottom of the body portion and to stiffen the body of the cap, said body portion having a screw-thread formed therein. 20

In testimony whereof I affix my signature in the presence of two witnesses.

ROBERT A. RUSSELL.

Witnesses:

EMMA WEINBERG,
LOUIS BRANDWIN.

It is hereby certified that Letters Patent No. 1,327,967, granted January 13, 1920, upon the application of Robert A. Russell, of New York, N. Y., for an improvement in "Caps for Bottles or Jars," were erroneously issued, by direct and mesne assignments, of one-third to Paragon Metal Cap Company, Inc., of Brooklyn, New York, a corporation of New York, one-third to Martin King, of New York, N. Y., and one-third to Leslie R. N. Carvalho, of Brooklyn, New York, whereas said Letters Patent should have been issued *one-third to the inventor, said Russell, one-third to Martin King, of New York, N. Y., and one-third to Leslie R. N. Carvalho, of Brooklyn, New York, as assignees, by mesne assignments*, of the entire interest in said invention, as shown by the records of assignments in this office; and that the said Letters Patent should be read with this correction therein that the same may conform to the record of the case in the Patent Office.

Signed and sealed this 30th day of March, A. D., 1920.

[SEAL.]

M. H. COULSTON,
Acting Commissioner of Patents.
